UNITED STATES PATENT OFFICE.

RICHARD L. FEARN, OF PHILADELPHIA, PENNSYLVANIA.

HEAT-SATURATION INDICATOR.

Application filed May 7, 1924. Serial No. 711,706.

My invention relates to thermal measuring devices and particularly to means for and methods of determining the transfer of heat.

5 One object of my invention is to provide a relatively small and simple device for indicating the transfer of heat in a furnace.

Another object of my invention is to provide a portable device for insertion into a 10 furnace in which a body is being heated, for determining and indicating the degree of heat saturation of said body.

It is highly desirable, in the heating of material, particularly when in large masses, 15 to be able to determine when the entire mass has been fully heated.

In practicing my invention, I provide a plurality of thermo-couples in circuit, and arranged to be severally responsive to a 20 source of heat and to the heat emitting from a body subjected to the heat of said source, the said circuit comprising an electrically-responsive device. When the electrically-responsive device indicates that both thermo-couples generate the same thermal electro-motive force, the body is fully heated.

In the single sheet of drawings,

Figure 1 is a view of an electric furnace in vertical lateral section, containing a body 30 to be heated and a thermal measuring device embodying my invention;

Fig. 2 is a top plan view of a thermal responsive device embodying my invention;

Fig. 3 is a side elevational view thereof; 35 and

Fig. 4 is a phantom perspective view of the arrangement of thermo-couples employed in my invention.

A furnace 11 comprises a plurality of refractory walls 12 and a heating means 13 of 40 any well known character, which in the preferred embodiment, comprises an electric heating element. A plurality of heating elements may be used if desired and located in 45 other portions of the furnace structure such as the side and the end walls. The furnace structure thus described is intended to be representative only and to illustrate a furnace with which certain members herein-after to be described may be operatively associated.

A body 14 to be heated comprising in its composition, material capable of absorb-

ing heat is supported in the furnace chamber and subjected to heat from the heating means 13.

An electrically-responsive device 15 such as an ammeter is connected in circuit with a thermal-responsive device hereinafter more fully described, the connecting conductors 60 being supported and protected by an elongated tubular structure 16.

The thermally-responsive device preferably comprises a highly refractory heat insulating member 17, of substantially disk 65 shape, that is supported in a bifurcated end of the tubular member 16 and fixedly attached thereto by bolts 18 and 19. The member 16 may be constructed in various ways, but I prefer a simple structure as 70 shown, comprising a plurality of interfitting sections and a handle 20. The arrangement of parts is such that the handle may be spaced from the disk 17 any desired distance by the insertion or removal of said 75 sections.

A plurality of thermo-couples are supported upon the disk 17 and separated thereby, and in the preferred embodiment, a pair of thermo-couples 21 and 22 are used, these 80 being connected in circuit with the electrically-responsive device 15 by conductors 23 and 24. The conductors 23 and 24 are led to the thermocouples through the tubular member 16 and are maintained in spaced relation by a perforated refractory disk member 25. A plurality of such spaced members are mounted in the sections of the member 16 in any suitable manner such as by use of pins 26.

In practice, the thermal-responsive device is inserted into the furnace chamber through one of a plurality of openings 27 in the furnace walls that may be located at convenient points to permit of disposing the device in any desired position relatively to the body being heated. The openings, of course, may be provided with closures (not shown) if desired. I have found it to be most convenient and practical to interpose the thermal-responsive device between the source of heat and the body being heated, as it is apparent that there is a temperature difference therebetween resulting in the transfer of heat from the source to the body proportional to the temperature difference. This

transfer of heat increases the temperature of the body, and the rate of heat emission therefrom increases proportionately. The refractory plate of the thermal-responsive device is interposed between the source and the body to be heated. The thermocouples are, therefore, subjected to the heat emitting from the source and the body, respectively, which causes electric potentials to be produced in the thermo-couples and a current to traverse the circuit proportional to their algebraic sum. The electrically-responsive device is actuated in accordance with the amount of current traversing the circuit. It is apparent, therefore, that the thermal electromotive force in the thermocouples is proportional to the amount of heat emitted from the heat source and the heated body, respectively, and that the resultant current produced in the circuit bears a substantially direct relation to the degree of heat saturation of the heated body.

Several ways of utilizing this relation are obvious. If the thermo-couples are connected in opposed series relation, the current in the circuit will be substantially zero when the heated body has reached substantially the point of heat saturation. An instrument 15 such as an ammeter, when properly calibrated, will indicate when this point is reached. A suitable control circuit 28 may be actuated by the current produced in the thermo-couple circuit, a convenient method being to connect the thermo-couples in series circuit relation therewith.

The device embodying my invention thus provides a relatively simple and inexpensive means for determining the heat transfer from a source to a heated body and the degree of heat saturation of the latter.

Various modifications may be made in the device embodying my invention without departing from the spirit and scope thereof, and I desire that only such limitations shall be placed thereon as are imposed by the prior art or are specifically set forth in the appended claims.

I claim as my invention:

1. The combination with a refractory heat-insulating member, of a plurality of thermo-couples respectively supported on the two opposite sides thereof, means for electrically connecting the thermo-couples in opposition to produce a resultant thermal electromotive force when subjected simultaneously to the temperatures of a source of heat and of a body heated thereby, and indicating electro-responsive means connected in circuit with said thermo-couples.
2. A testing device for a body heated by external means, comprising an electrically-

responsive device, a plurality of thermo-couples electrically connected in opposition, means for connecting said thermo-couples in series-circuit relation to said electrically-responsive device, and a refractory heat insulating member located between said thermo-couples for causing said device to be actuated in accordance with the heat emission of the body relatively to the heat emission of the external heating means.

3. A temperature-indicating device for measuring the temperature difference between a source of heat and a body to be heated, said device comprising a support of refractory heat-insulating material, thermo-couples located one on each side of said support and secured thereto, said support being effective to shield the respective thermo-couples from the sources of heat, affecting the one thermo-couple from the other, an electro-responsive instrument, and means for electrically connecting said thermo-couples to said instrument.

4. In combination, a temperature-responsive device for determining the degree of heat transfer from a source of heat to a body to be heated, said device comprising a thermo-couple for measuring the temperature of said source, a thermo-couple for measuring the temperature of said body, means for shielding the heat affecting the one thermo-couple from the other thermo-couple, said thermo-couples being supported by said means, and means for electrically connecting said thermo-couples.

5. The combination with a relatively thin refractory heat insulating member, of a pair of thermocouples, one thermo-couple being secured to one flat side of the refractory member and the other thermo-couple being secured to the other flat side thereof, means for connecting said thermo-couples in opposition in an electric circuit, and an indicating means in said circuit for indicating the difference of electro-motive forces of the two thermo-couples.

6. In a device for measuring the relative heat emission of two thermally related bodies, a relatively thin refractory heat insulating member, a hollow handle secured thereto, a pair of thermocouples secured respectively to the opposed flat sides of said refractory member, an indicator and conductors traversing said hollow handle for electrically connecting said thermocouples in opposed series circuit relation to said indicator.

In testimony whereof, I have hereunto subscribed my name this thirtieth day of April 1924.

RICHARD L. FEARN.
